UNITED STATES PATENT OFFICE.

AUSTIN H. CAMPBELL, OF PROSPECT, PENNSYLVANIA.

CHIMNEY OR SMOKESTACK VENTILATOR.

Application filed April 17, 1922. Serial No. 553,835.

To all whom it may concern:

Be it known that I, AUSTIN H. CAMPBELL, a citizen of the United States, residing at Prospect, in the county of Butler and State 5 of Pennsylvania, have invented certain new and useful Improvements in Chimney or Smokestack Ventilators, of which the following is a specification.

This invention relates to new and useful 10 improvements in chimney or smoke stack ventilators, and has for its object to provide a device of this character which will prevent the wind or unnatural draft from entering the chimney or smoke stack and 15 thus materially dampen or diminish the fire but will, at the same time, allow the natural draft through the chimney or smoke stack.

With the foregoing and other objects in view that will appear as the nature of my 20 invention is better understood, the same consists in the novel features of construction, combination and arrangement of parts illustrated in the drawings and more particularly pointed out in the appended claim.

25 In the accompanying drawings, which are for illustrative purposes only and are therefore not drawn to scale:—

Figure 1 is a side elevation, illustrating the application of my invention to the smoke 30 stack of a locomotive.

Figure 2 is a fragmentary rear elevation of the smoke stack with my ventilator applied, the parts represented on an enlarged scale.

35 Figure 3 is a vertical transverse section, taken on line 3—3 of Figure 2 and Figure 4 a top plan view of my device.

Referring to the drawings for a more 40 particular description of my invention and in which drawings like parts are designated by like reference character throughout the several views, A designates the boiler of a locomotive, B the smoke stack and C my improved ventilator, as a whole, applied to 45 the smoke stack.

Specifically, my device comprises an annular rim or support *a* composed of two corresponding semi-circular sections 1 and 2 which completely encircle or embrace the smoke stack or chimney near the top and are 50 formed at their adjacent or abutting ends with upstanding and depending lugs 3 and

4, respectively, fastened together by bolts 5 or other equivalent means.

The rim or support *a* is provided on its outer surface with an annular flange or bead 6 which fits in a corresponding recess 7 formed in the inner edge of the ring or carriage 8 completely encircling and rotatable in either direction on said rim or support. 55 The ring or carriage 8 is provided at the front with an integral semi-circular offset rim 9 which carries the rigid semi-circular sheet metal shield or deflector 10 which extends a suitable distance above the top of 60 the smoke stack or chimney and is movable with the ring or carriage.

The rim or support *a* is secured to the smoke stack or chimney by the depending lugs 11 and is formed in its bottom edge with an annular rack 12 whose teeth intermesh with those of a pinion 13 rotatably mounted in the hanger or bearing bracket 14 bolted, as at 15, to the bottom wall or edge of the rim or support. The shaft 16 of the pinion 13 is provided with a pulley 17 to which is attached one end of a cable 18 or other flexible element whose free end extends to within convenient reach of the operator and whereby the shield or deflector 80 may be turned to face the wind. By this arrangement, the wind or unnatural draft is prevented from entering the smoke stack or chimney and thus depress or diminish the fire, while the natural draft of air is permitted to pass through the openings 19 between the outer edge or wall of the ring or carriage 8 and the inner wall of the rim 9 and enter the same.

While my device is shown in the present 90 illustration as applied to the smoke stack of a locomotive, it may be used with equal facility in connection with stationary boilers or chimneys.

From the foregoing description taken in 95 connection with the drawings, it is thought that the construction, operation and advantages of my invention will be readily understood without requiring a more extended explanation.

Having described my invention what I claim as new and desire to secure by Letters Patent, is:—

A stack ventilator comprising a rim adapt-

ed to be applied to the stack and provided upon its outer face with an outstanding annular flange, a carriage surrounding the rim and provided at its inner face with an annular recess which snugly receives said flange, means mounted on the rim for turning the carriage upon the rim, a frame car-

ried by the carriage and having portions spaced from the edge of the carriage and a semi-cylindrical shield mounted upon said spaced portions of the frame.

In testimony whereof I affix my signature.

AUSTIN H. CAMPBELL.
